ELECTROMAGNETIC DEVICE

Francis M. Joseph, Cliffside Park, N. J., assignor
to Bendix Aviation Corporation, South Bend,
Ind., a corporation of Delaware

Application January 23, 1941, Serial No. 375,705

2 Claims. (Cl. 175—335)

This invention relates to electro-magnetic devices, and particularly to electro-magnetic devices of the "solenoid" class, in which the magnetic circuit includes a closeable gap at a point within the coil or coils of wire through which the energizing current passes.

An object of the invention is to provide an electro-magnetic device, of novel construction, for the actuation of a part to be shifted from one position to another. If such a part is a valve or other control element of an internal combustion engine or other machine, it is probable that the operation thereof may involve a splashing or seepage of oil or liquid fuel into the interior of the electromagnetic device, and a subsequent leakage of such liquids from the device, and onto the surfaces of adjacent apparatus, to the detriment of the latter. Another possibility is the entry of explosive vapors, creating a hazard because of possible contact with switch elements, or with sparks emanating from such switch elements. Such a hazard is guarded against in the present invention; one of the objects of this invention being to provide an electromagnetic device that includes a liquid-tight and vapor-tight chamber, with the switch elements housed therein and thereby protected against contact with any fluid other than ordinary air.

Another object of the invention is to provide, in a device having a fluid-tight, switch-containing chamber, a second chamber containing the actuating means for the switch elements of said first-named chamber, and a sealing wall interposed between said two chambers to prevent passage of fluid from one to the other, but without interfering with the transmission of motion between movable parts located in both said chambers.

Another object is to provide means for maintaining fluid circulation in said second chamber, thus rendering impossible the development of a "fluid lock"—meaning by this term any condition of fluid accumulation which might interfere with the free operation of the movable parts of the device.

A further object is to provide a novel control of the flow of current to an electro-magnetic device.

Another object is to provide current flow control means including switch mechanism and switch actuating means of novel construction, and having a novel mode of operation.

These and other objects of the invention will become apparent from inspection of the following specification when read with reference to the

accompanying drawing wherein is illustrated the preferred embodiment of the invention. It is to be expressly understood, however, that the drawings are for the purpose of illustration only, and are not designed as a definition of the limits of the invention, reference being had to the appended claims for this purpose.

In the drawing,

Fig. 1 is a longitudinal sectional view of a device embodying the invention;

Fig. 2 is an end view, from the right of Fig. 1, after removal of the cover plate at said right-hand end;

Fig. 3 is a transverse sectional view along line 3—3 of Fig. 1;

Fig. 4 is a diagram of the control circuit, including a perspective view of the switch elements; and

Fig. 5 is a perspective view of the plunger, or movable magnetic element, together with the plunger rod.

In the drawing the source of current is shown at 11, (Fig. 4) the solenoid winding at 12, the novel switch elements at 13 and 14, and a conventional switch at 15. The latter may be a toggle switch or any other common type of manually operable switch, while the switch 13, 14 is to be automatically operable. To this end its contacts 16, 17 are normally pressed together by reason of the resilient nature of the arms 13 and 14, particularly the former, and the fact that said arm 13 is initially flexed sufficiently to insure maintenance of firm engagement of contacts 16 and 17 until forced apart by external pressure, automatically applied in the manner hereinafter described.

Numerical 21 indicates a cup-shaped housing for a spool 22 on which the solenoid coil 12 is wound, the housing 21 being preferably formed as a steel (magnetic) stamping, and internally threaded at its open end to receive a closure plate 24 and an annular nut 26 to hold the closure plate in position. The closure plate 24 has a central opening to receive magnetic element 27, the latter having a lip expanded against the opening of the plate for fixation thereto. The element 27 extends inwardly in concentric relation to the coil 12 and constitutes the fixed pole-piece of the magnetic circuit of the solenoid; the movable pole-piece being shown at 28. This movable pole-piece (plunger) 28 has pinned thereto (at 29) a rod 31 of non-magnetic material, and at its opposite end has a threaded bore to receive the threaded shank 32 of a stud 33 which terminates in a head 34 adapted to move

to the left (from the position shown in Fig. 1) along with the plunger 28 in response to passage of current through winding 12 and the resultant closure of the gap in the magnetic circuit; the said gap in the magnetic circuit being normally maintained by the pressure of yieldable spring 36 (seated in the counterbore of pole-piece 27) upon the shoulder 37 adjacent the tapered part 38 (see Fig. 5) of the plunger 28.

When the head 34 is moved to the left it strikes against, and exerts pressure upon, the interposed tab 41 of the current conducting arm 13; and this leftward pressure serves to separate the contact 16 from the contact 17, in the manner indicated in Fig. 4. The coil 12 remains energized, however, although with lower energy consumption due to the shunt circuit by way of resistor 23; therefore the rod 31 and the valve (not shown) or other part to be actuated thereby, will be held in the actuated position. (As shown in Fig. 1, resistor 23 is a coil superimposed on coil 12.) Upon de-energization of the coil 12 (by opening switch 15) the magnetic flux drops almost instantly to zero, and spring 36 instantly returns the plunger 28 and stud 33 to the positions shown in Fig. 1, whereupon the initially stressed resilient arm 13 springs back toward arm 14 and thus re-engages the contact 16 with the contact 17; but no current flows therethrough, as switch 15 is now open.

The novel means for maintaining the switch chamber 51 fluid-tight is shown as including a flexible sealing member 52 clamped at its periphery between the coil housing 21 and the switch housing 53, while its central portion 54 is clamped between the end of plunger 28 and a shoulder formed on the stud 33 at the point where the threaded shank 32 merges into said stud. Between this central portion 54 and the peripheral portion there is sufficient slack in the sealing diaphragm 52 to prevent the development of any substantial stress or strain as the central part of the diaphragm moves back and forth with the remainder of the plunger and stud assembly. As the threaded shank 32 is shorter than the threaded bore of the plunger 28, the stud 33 can be screwed in far enough to bring its shoulder tightly against the diaphragm 52 at the point of engagement of said diaphragm with the end of the plunger. Thus there is established a positive barrier to the passage, into the switch chamber 51, of any liquid or vapor that may have found its way into the annular space around the plunger 28. In lieu of passing into the chamber 51 such liquid or vapor will eventually pass back to the outer (left-hand) end of the unit by way of the longitudinally extending grooves 56 (see Fig. 5), thus returning to the interior of the intake manifold or other chamber of the engine (or other machine) on which the housing 21 is mounted, and in which is contained the valve or other part (not shown) to be actuated by the plunger rod 31.

The winding 12 and resistor 23 are shown as provided with terminal posts 71, 72 and 73 passing through openings in the parallel ends of the housings 21 and 53, and through openings in the

peripheral portion of diaphragm 52 and spacer ring 74; the posts 71, 72 and 73 being insulated from all these parts by means of suitable non-conducting bushings 76 and 77. Terminals 71,

5 72 and 73 are fixed to the head of spool 22 in any suitable way, as by being molded therein; and as these terminals have threaded ends to receive suitable nuts 78, 79 and 80, it will be seen that the tightening of these nuts will apply further 10 clamping pressure to the parts, including the periphery of the sealing element 52. A boss 81 on housing 53 is provided with an opening 82 through which passes the wire that makes electrical connection between post 73 and the 15 source 11.

What is claimed is:

1. In a device of the character described, a spool of insulating material, a plurality of current conducting terminal posts embedded therein, a pair of windings on said spool, one of which is electrically connected between two of said posts, the other winding being connected between one of said first two posts and a third post, means normally establishing direct electrical connection between said two first-named terminal posts, thereby short-circuiting said first-named winding, upon current flow to one of said two first-named posts, by way of said third post and said second-named winding, 20 30 means for causing such current flow, circuit-breaking means responsive to such current flow to break the direct electrical connection between two first-named terminal posts, and thus divert the current flow to a path which includes said first-named winding and places said first-named winding in series connection with said second winding, 35 a housing for said windings and spool, and a second housing for said circuit-breaking means, said two housings being held together by 40 means including said terminal posts.

2. In a device of the character described, a spool of insulating material, a plurality of current conducting terminal posts embedded therein, a pair of windings on said spool, one of which is electrically connected between two of said posts, the other winding being connected between one of said first two posts and a third post, means normally establishing direct electrical connection between said two first-named terminal posts, thereby short-circuiting said first-named winding upon current flow to one of said two first-named posts, by way of said third post and said second-named winding, means for causing such current flow, circuit-breaking means responsive to such current flow to break the direct electrical connection between two first-named terminal posts, and thus divert the current flow to a path which includes said first-named winding and places said first-named winding in series connection with said second winding, a housing for said windings and spool, and a second housing for said circuit-breaking means, a fluid seal between said housings, said two housings and said fluid seal being held together by means including 50 55 60 65 said terminal posts.
